UNITED STATES PATENT OFFICE.

PAUL E. JEANMAIRET, OF ELGIN, ILLINOIS.

ESCAPEMENT-WHEEL.

1,044,054.

Specification of Letters Patent.

Patented Nov. 12, 1912.

Application filed January 24, 1912. Serial No. 673,097.

To all whom it may concern:

Be it known that I, PAUL E. JEANMAIRET, a citizen of the United States, residing at Elgin, in the county of Kane and State of Illinois, have invented certain new and useful Improvements in Escapement-Wheels, of which the following is a specification.

The present invention involves certain improvements in escapement wheels for 10 watches of the type set forth and described in my Letters Patent No. 898,479, issued September 15, 1908, and wherein a wheel is employed and so formed as to provide lubricant holding means on the teeth thereof.

15 The object of the improvements herein-after presented in detail is to provide an escapement wheel such as used particularly for watch and clock movements, in which the lubricant holding pockets may be readily 20 formed in the process of cutting the wheel.

The improvements also contemplate a peculiar location of the lubricant pockets in respect to the teeth of the wheel whereby the feeding of the lubricant to the pallet 25 engaging portions of the teeth by centrifugal action is facilitated.

For a full understanding of the present invention, reference is to be had to the following description and to the accompanying drawings, wherein—

Figure 1 is a side view showing an escapement wheel embodying the invention in operative relation to a common form of pallet. Fig. 2 is a view in side elevation of one of 35 the teeth, a fragment of the wheel body being shown and the parts being seen on an enlarged scale. Fig. 3 is an edge view of the parts seen in Fig. 2.

Throughout the following detail description and on the several figures of the drawings, similar parts are referred to by like reference characters.

The escapement wheel illustrated in the drawings is of the ordinary type in so far 45 as its general formation is concerned and is denoted at 1. The various teeth 2 of the wheel are adapted to coöperate with the pallet 3 in the customary way, the latter being provided with the stones 4. In making the 50 wheel 1, it is contemplated to form the teeth 2 slightly wider near their outer ends than usual in order to readily provide pockets or recesses 5 in the curved edge portions of said teeth, arranged transversely on the edges 55 with respect to the diameter of the escapement wheel, that is, substantially parallel to

the axis of the wheel. The pockets 5 are of somewhat semi-circular form and are sufficiently deep that they will receive a drop of lubricating oil when the latter is applied thereto, and the two edges of each recess are parallel to each other, as shown. The said pockets or recesses 5 are arranged substantially parallel to each other on the different teeth. The oil once received in a 60 pocket 5 is fed to the head or outer extreme portion of the teeth to reduce to a minimum the friction between the stones 4 of the pallet and the wheel.

As above noted, the lubricant pockets 5 are arranged on the curved side of the teeth and formed as close as possible to the heads of said teeth, this being advantageous in order that the lubricant may freely flow to the portions of the teeth where most needed. 75 As a matter of fact, a portion of the head of each tooth is cut out in forming the lubricant pocket 5 therein, as will be readily observed upon reference to the drawing, the pocket extending transversely the entire 80 width of the face of the tooth in a direction parallel to the axis of the escapement wheel. The edge of the substantially semi-circular channel or pocket which is formed farthest away from the axis of the wheel is 85 a slight distance inwardly from the outer edge of the tooth in which the channel or pocket is formed.

In the use of the invention, when the oil 90 is applied to the ends of the teeth 2, it will drop into the pockets 5 and in the operation or motion of the escapement will feed to the stones 4 by capillary action. As the recesses, or pockets, 5 are disposed in substantial parallelism to the axis of the escapement wheel, 95 the centrifugal action exercised by the rotation of the escapement wheel tends to throw the oil contained in the pockets, or recesses, toward the deepest portions thereof, these being the portions of the recesses which are located farthest away from the axis of the wheel and somewhat inwardly from the edges of the recesses which are nearest to the outer edges of the teeth. This action results in a two-fold advantage, firstly, it has a 100 tendency to hold the oil in the pockets for a greater length of time, as the throw is in the direction of the deepest portions of the pockets and not outwardly therefrom, as will be obvious, but this tendency of the oil to collect in the region of greatest depth of the pockets causes an exceedingly minute 105 110

quantity of the oil to be forced over the edges of the recesses which are farthest from the axis of the escapement wheel and nearest to the outer edges of the teeth, which results in the feed to the outer edges being exceedingly small. This fact, taken in connection with the fact that the recesses are disposed on the sides of the teeth which are curved, by which provision the contact between the straight edges of the stones 4 and the said sides of the teeth is only very slight on account of the curvature of the latter, results in the second advantage that the feed of oil is excessively minute and a quantity once placed in the recesses will last a great length of time.

Having thus described the invention, what is claimed as new is:

1. As an article of manufacture, an escapement wheel comprising a body and arms extending outwardly therefrom, one of said arms having a lubricant containing recess formed therethrough substantially parallel to the axis of the body, said recess being adjacent the outer end of the arm in position for delivering lubricant to the end of the arm.

2. As an article of manufacture, an escapement wheel comprising a body and arms extending outwardly therefrom, one of said arms having a lubricant containing recess formed therethrough substantially parallel to the axis of the body said recess being adjacent the outer end of the arm in position for delivering lubricant to the end of the arm, said recess opening at the opposite edge of the arm from that adapted to engage the pallet.

3. As an article of manufacture, an escapement wheel comprising a body, and arms extending outwardly therefrom, each having a recess extending transversely through the material of the respective arm substantially parallel to the axis of the body, each of the recesses being adjacent the outer end of the respective arm in position for delivering lubricant from the respective recess to said outer end.

In testimony whereof I affix my signature in presence of two witnesses.

PAUL E. JEANMAIRET.
